UNITED STATES PATENT OFFICE

HENRY K. RYDER, OF LAUREL, MONTANA

GAS SAVER

Application filed April 25, 1931. Serial No. 532,854.

My invention relates to an auxiliary air inlet for gas engines and has for its primary object to provide an auxiliary air inlet adapted to be associated with the intake manifold of a gas engine and operable by the suction of the engine to admit an extra supply of air in proportions necessary to produce a mixture within the intake manifold which is best suited for operating the engine.

Another object of the invention is to provide a device of the above-mentioned character which is simple and durable in construction, reliable and efficient in operation and inexpensive to manufacture.

Other objects and advantages of the invention will be apparent during the course of the following description.

In the accompanying drawing, forming a part of this specification and in which like numerals are employed to designate like parts throughout the same,

Fig. 1 is a front elevation view of the device applied to the intake manifold of a gas engine,

Fig. 2 is a side view of the device,

Fig. 3 is an enlarged side view, partly in section,

Fig. 4 is a detail sectional view taken on lines 4-4 of Fig. 3,

Fig. 5 is a cross section taken on lines 5-5 of Fig. 4, and,

Fig. 6 is a sectional view of a modified form of inlet nipple.

In the drawing, wherein for the purpose of illustration, I have shown a preferred embodiment of my invention, the numeral 5 denotes the intake manifold of a conventional type of gas engine.

Referring more particularly to my invention, the device consists of a substantially T-shaped pipe 6, the stem of the pipe having its lower end coiled, as at 7, to provide a right angular extension 8 having external screw-threads 9, through the medium of which the device is connected to the threaded opening in the intake manifold, to which the vacuum line 10 is ordinarily connected. The arms 11 of the pipe are curved downwardly and inwardly, as at 12, the terminals 13 of the arms

extending downwardly in spaced parallel relation. The terminals 13 are connected by a cross-brace 13' which fits snugly against the extension 8 and pipe 6 and holds the parts against relative vibration. The lower ends of terminals 13 are provided with interior screw-threads to receive the head 14 of the inlet nipple 15 which is screwed therein. A cap or plug 16 is screwed in the lower end of the nipple 15 having a central orifice 17 surrounded by the valve seat 18 to receive the ball valve 19. The lower end of the cap is provided with an inlet opening 20 in alignment with the orifice 17. The upward movement of the ball valve is limited by the tube 21 which is disposed within the upper end of the nipple 15, the upper end of the tube being screwed into the bore 22 through the head 14 of the nipple. The lower end of the tube is provided with apertures 23 in its walls. The head 24 of the stem is provided with interior screw-threads 25 to permit attachment of the vacuum line 10 with the device.

A modified form of cap for the air inlets is shown in Fig. 6, which consists of a conical body 26 having its upper end provided with external screw-threads 27 to permit the cap to be screwed into the lower end of the nipple 15. In the upper end of the body 26 is a valve seat 28 having a central orifice 29 on which the ball valve 19 is adapted to be seated. The walls of the body are provided with a series of spaced apertures 30 through which air is admitted.

In operation, it will be seen that when the device is attached to the intake manifold of a gas engine an auxiliary supply of air will be admitted to the manifold, to mix with the gas. The upward movement of the valves is limited by the tubes 21, so that no matter how great the suction is the passages of the arms will not be closed. As the suction decreases the ball valves will automatically seat closing the orifices 17, cutting off the auxiliary supply of air.

It is to be understood that the form of my invention herewith shown and described is to be taken as a preferred example of the same and that certain changes in the shape,

size and arrangement of the parts may be made without departing from the spirit of the invention or the scope of the subjoined claim.

5 Having thus described my invention, I claim:—

- An auxiliary air inlet for the intake manifold of a combustion engine including a downwardly extended suction pipe coiled to 10 provide a substantially horizontal extension for threaded engagement with an intake manifold to discharge thereinto, oppositely disposed tubular arms on the pipe above the coil and extending downwardly below the 15 coil in substantially parallel relation, ball valves for normally closing the lower ends of said arms, said valves being liftable by suction to admit fresh air to the arms and pipe, and a rigid spacing connection between 20 the arms and engaged by the pipe and the extension.

In testimony whereof I affix my signature.

HENRY K. RYDER.
